UNITED STATES PATENT OFFICE.

HARRY P. MACDONALD, OF MONTCLAIR, AND WILLIAM A. ROEDELL, OF JERSEY CITY, NEW JERSEY, ASSIGNEES TO THE SNEAD AND COMPANY IRON WORKS, OF JERSEY CITY, NEW JERSEY, A CORPORATION OF NEW JERSEY.

METHOD OF FORMING SAND MOLDS.

1,065,540.

Specification of Letters Patent. Patented June 24, 1913.

Application filed January 22, 1912. Serial No. 672,567.

To all whom it may concern:

Be it known that we, HARRY P. MACDONALD and WILLIAM A. ROEDELL, citizens of the United States, residing, respectively, at 5 Montclair, in the county of Essex, and Jersey City, in the county of Hudson, in the State of New Jersey, have invented certain new and useful Improvements in Methods of Forming Sand Molds, of which the following is a specification.

The invention relates to a method of forming sand molds, particularly to the method known as the roll ramming method. It has for its primary objects the provision 15 of an improved method of filling the mold flasks with sand; the provision of an improved method of filling the mold flasks with sand taken directly from flasks of molds from which the castings have been 20 removed; and the provision of improved apparatus for carrying out the method herein described. These, together with such other objects as may hereinafter appear, are obtained by means of a method 25 and apparatus illustrated in the accompanying drawings wherein

Fig. 1 is a side elevation of a roll ramming molding machine showing our improved flask filling apparatus in position 30 to fill a flask, Fig. 2 is an end elevation of Fig. 1 diagrammatically illustrating various steps of our improved method and Figures 3, 4, and 5 are respectively plan, side, and end views of our improved filling or dumping mechanism.

In order to obtain a better understanding of the method employed in filling the flasks, the apparatus will first be described, reference being had to Fig. 1. From inspection of this figure it will be seen that in carrying out our invention we employ a roll ramming machine comprising a roll 3 which is adapted to travel back and forth on the track 4 and which is actuated in the usual 40 manner by means of a motor 5 through the gearing 6 and shaft 7. The shaft 7 is provided with a pinion (not shown) which engages a rack 8 secured to a frame 9 supported by the axle 10 of the roll 3. The 45 driving mechanism is suitably mounted in the frame work 11 and the track 4 is hinged as at 5^a so that the portion 4' of the track may be lifted free of the flask 12 when the

latter is being filled with sand, such portion 4' normally resting on the top of the flask 55 12 when the sand is being rammed by the roller 3. The portion 4' is elevated by means of the counterweight 13 through the cable 14 passing over the sheaves 15 and 16, the counterweight and track being balanced 60 so that the track will remain either in operative or in inoperative position without the use of locking means. The flasks are placed in position and removed by means of the air hoist 17 supported from an overhead 65 I-beam 18 by means of the trolley 19.

The flasks are filled when in position on the ramming machine from a dumping box 20 supported by the hooks 21 of the air hoist 17. Referring particularly to Figures 70 3, 4, and 5, it will be seen that the dumping box has an open front end 22 and is covered by the coarse screen 23. A beam 24 extends across the bottom of the box and is provided at either end with an angle or clip 25, 75 the clips being recessed to receive the hooks 21 of the air hoist. The recesses are placed off center, see Fig. 5, and brackets 26 are secured to the ends of the box and are adapted to bear against the hooks 21 when 80 the box is supported from the air hoist. By this arrangement the center of gravity of the box is to one side of the point of support and the box is prevented from tilting and dumping its contents out of the open 85 side or front 22. The brackets 26, however, prevent the box from tilting in the opposite direction. When the dumping box is brought into position over the flask 12 on the ramming machine, it is tilted by means 90 of the handles 27, and after the box has been dumped it is dragged away from the flask by means of the handles 28.

Heretofore it has been the practice to remove the sand remaining in the flasks after 95 the mold has been cast to a bin or other receptacle where it is broken up and sifted before being reused in forming new molds. By our improved method this step is eliminated and the sand remaining in the flasks, 100 after the removal of the casting, is dumped into the dumping box 20 through the screen 23, which breaks up and sifts the sand, which is again agitated when the dumping box 20 is tilted to fill the flask in position on 105 the ramming machine.

In Fig. 2 we have diagrammatically illustrated various steps of our improved method. This figure shows a flask 12' from which the casting has been removed but 5 which still contains the sand. The air hoist 17 is moved in position above this flask and the hooks 21 attached thereto. The flask is then lifted and its contents dumped into the dumping box 20 which is placed adjacent to 10 the flask on the foundry floor. After the flask is dumped, the hoist 17 is moved in position above the ramming machine and the flask is placed in position thereon over a pattern. The track 4' is lowered into position 15 and the hoist is then brought back and picks up the dumping box 20, now full of sand, and carries it back to the machine where the box is dumped over the flask into which a sufficient amount of sand has been 20 riddled by hand to provide a coating of fine sand over the pattern. The dumping box 20 is then removed and the sand is rammed in the flask by the roll 3. After the flask is rammed, it is picked up by the air hoist 25 and is carried back and matched with another flask to form a completed mold. The operation can then be repeated.

It will be apparent that the method is simple and effective and does away with a 30 great deal of labor and intermediate operations involving expense. It will also be apparent that the sand is thoroughly broken up and sifted by the double operation of first emptying it into the dumping box and 35 then redumping it into another flask in position on the machine. If, owing to the difference in size between flasks, there be an insufficient amount of sand in the dumping box to fill the particular flask on the machine, the needed amount may be readily supplied by hand. Other advantages will 40 occur to those familiar with the art.

Having thus described our invention and illustrated its use, what we claim as new

and desire to secure by Letters Patent is the 45 following:

1. The herein described process of forming sand molds which consists in dumping the sand remaining in a flask after the removal of the casting therefrom into a receptacle through a screening surface to break up the solid body of sand, and then in dumping the sand from the receptacle into a flask for reuse. 50

2. The herein described process of forming sand molds which consists in dumping the sand remaining in a flask after the removal of the casting therefrom into a receptacle having an open end, in carrying the receptacle to a flask to be filled and then in 55 tilting the receptacle to cause the sand to slide out the open end into the flask. 60

3. The herein described process of forming sand molds which consists in dumping the sand remaining in a flask after the removal of the casting therefrom into a receptacle having a screen on its top and an open end, in carrying the receptacle to a flask to be filled and then in tilting the receptacle to cause the sand to slide out the 65 open end into the flask. 70

4. The herein described process of breaking up and preparing for re-use the sand remaining in a flask from which the casting has been removed, which consists in picking 75 up the flask and dumping it into a receptacle to break up the sand, and then in again agitating the sand by picking up the receptacle and dumping the sand into a flask for reuse.

In testimony whereof we have hereunto 80 signed our names in the presence of the two subscribing witnesses.

H. P. MACDONALD.
WILLIAM A. ROEDELL.
